Erwood Co., Crystal Lake, Ill., a corporation of
Illinois

Application September 13, 1947, Serial No. 773,829

14 Claims. (Cl. 274—10)

1

The present invention relates in general to intermittently operable apparatus, and more particularly to automatic phonograph record disc feeding and playing apparatus.

Apparatus of the character mentioned may comprise the combination, with phonographic record playing apparatus, of mechanism for automatically delivering phonographic record discs successively in playing position in the record playing apparatus. Such mechanism also may include means for controlling the record playing and disc feeding apparatus in predetermined sequence in order, at the conclusion of the playing of a record disc, or at any time during the playing of a disc, to retract the sound pick-up element of the record playing mechanism from playing position, to deliver a record disc in playing position while the pick-up device is in retracted position, and to return the pick-up device to playing position with respect to the record so delivered, whereby to provide for the playing of a series of record discs successively, in automatic fashion, in the phonograph apparatus.

An important object of the present invention is to provide inexpensive, simplified apparatus of the character described having a minimum number of operating parts, affording improved performance and adapted for manufacture at low cost, the invention, to this end, contemplating apparatus many of the constituent parts of which may readily and suitably be manufactured as sheet metal stampings.

Another important object is to provide intermittently operable apparatus of the character mentioned adapted normally to be retained in inactive condition, thus eliminating operational noise, including means automatically operable at predetermined intervals and manually operable, at any time, to activate the apparatus for the performance of its operating cycle, including the return of the apparatus to inactive cocked position ready for a repeat performance of its operating cycle; a further object being to provide apparatus comprising turntable driving means normally held stationary in cocked, inactive position and adapted when activated to be driven in one direction only for the performance of the operating cycle of the apparatus.

Another important object is to form said driving means as a shaft adapted for axial movement between active and inactive position, including means for drivingly turning said shaft when the same is in active position; a further object being to provide means normally urging said shaft axially toward active position and latch

2

means for retaining the shaft in inactive position; a still further object being to provide means for locking the shaft against rotation in a predetermined relative angular position when the same is latched in axially shifted inactive position; yet another object being to provide simplified means manually operable to release the latch at will, and automatically operable to release the latch in response to the occurrence of predetermined operating conditions, to initiate the operating cycle of said intermittently operable mechanism.

Another important object is to provide simplified driving mechanism intermittently operable for the sequential activation of mechanism such as a phonographic record feeding device and record playing apparatus, said driving mechanism comprising a shaft having cam means thereon for raising, lowering, and swinging the sound pick-up device of the record playing mechanism and for actuating the record delivery mechanism in timed relationship; a further object being to provide adjustable stop means controlled by said shaft, as by means of a cam thereon, to determine the initial or starting position of the pick-up device when advanced to record playing position following the delivery of a record disc in playing position in the apparatus.

Another important object is to provide improved and simplified means for axially shifting the shaft to retracted inactive position at the conclusion of its operating cycle of movement; a further object, in this connection, being to utilize a spring pressed lever adapted to apply increasing axial thrust on said shaft, as it reaches the conclusion of its operating cycle, in combination with means operable to retain said shaft in axially projected active position against the influence of said spring pressed lever until said shaft reaches a predetermined relatively angular position at the end of its operating cycle.

Another important object is to provide improved magazine means for supporting one or more phonographic record discs in position for successive delivery into playing position, as on the turntable of a record playing device; a further object being to provide improved and simplified edge pushing mechanism for shifting the lowermost record, in the record stack, to release the same for delivery on the turntable; a still further object being to provide edge pushing mechanism in the form of a plate mounted on a rockable support for edge pushing purposes, said plate being turnable to present any selected one of several edge pushing shoulders in pushing position whereby to accommodate the pushing mechanism

to record discs of unlike size, such as the standard 10" and 12" phonographic record discs.

Another important object is to utilize the adjusting movement of the edge pushing mechanism to adjust the stop mechanism which determines the starting position of the pick-up device when advanced to record playing position by operation of the intermittently operable driving mechanism.

Another important object is to provide intermittently operable driving mechanism for phonographic apparatus, including a record disc turntable, comprising an axially movable shaft carrying a gear wheel thereon, the shaft being normally retained in axially retracted position and being axially projectable into active position engaging said gear wheel with a driving gear formed on said turntable, whereby the rotation of the turntable may drive said shaft when the same is in axially projected active position; a further object being to form said gear wheel and gear as so-called beveled elements rotating on axes intersecting at an angle of the order of 90°; a still further object being to form said gear and gear wheel as sheet metal stampings; yet another object being to form the turntable as a sheet metal stamping with the gear built into the turntable as an integrated part thereof.

Another important object is to provide a simplified manually operable control adapted when in neutral position to condition the apparatus for automatic operation, said control being movable from neutral position in one direction to lock the automatic mechanism in inoperative position to provide for so-called "manual" operation of the record player, said control being movable in another direction from neutral position at will, during the playing of a record, to reject the record being played by causing operation of the automatic record changing mechanism.

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a top plan view of phonographic apparatus embodying the invention.

Fig. 2 is a view of the apparatus as seen from its under side.

Fig. 3 is a sectional view taken substantially along the line 3—3 in Figs. 1 and 2.

Figs. 4, 5 and 6 are sectional views taken substantially along the lines 4—4, 5—5, and 6—6 in Fig. 3.

Fig. 7 is a sectional view taken substantially along the line 7—7 in Figs. 1 and 2.

Figs. 8, 9, 10 and 11 are sectional views taken respectively along the lines 8—8, in Fig. 7, 9—9, in Fig. 2, 10—10, in Fig. 9, and 11—11, in Fig. 7.

Fig. 12 is a sectional view taken substantially along the lines 12—12 in Figs. 2 and 3; and

Fig. 13 is a sectional view taken substantially along the line 13—13 in Fig. 1.

To illustrate the invention, the drawings show a record player 11 comprising a support plate 12 carrying a record turntable 13 in position to support a record 14 in playing position thereon. To this end, the plate 12 carries a turntable mounting member in the form of a bushing 15 formed with suitable clamp means 16, at one end, whereby the bushing may be non-turnably secured to the plate 12.

The turntable 13 may comprise a sheet metal stamping, having a downwardly turned marginal rim 17 and a central opening fitted with a journal sleeve 18 adapted to fit upon the bushing 15, so that the turntable may be mounted for rotation freely on the bushing. A ring 19 may be provided to form a step bearing disposed between the lower end of the sleeve 18 and the plate 12. The lower end of the sleeve 18 also may be formed to provide a gear 20, preferably by flaring the lower end of the sleeve 18 outwardly to form a circumferential flange, and cutting gear teeth in said circumferential flange. The central portions of the turntable may also be strengthened and reinforced, and the sleeve 18 braced by means of a dished washer 21 welded to the turntable and to the lower end of the sleeve 18 adjacent the gear 20, the upper end of the sleeve being secured to the body of the turntable at the center thereof. The gear 20 provides driving means for a driven means comprising another gear and an axially shiftable rotatable shaft hereinafter described.

The turntable may be, and preferably is, driven by an electric motor 22, in any suitable or preferred fashion. As shown, the motor may be secured to the plate 12, on the underside thereof, and may have a shaft 23 extending through the plate and carrying a turntable driving roller 24 in position to drivingly engage the rim of a wheel 25, said wheel being supported on the plate 12 in position to drivingly engage the downwardly turned rim 17 of the turntable. Operation of the motor may be controlled by a suitable switch 26, preferably mounted on the plate 12, the switch having its manually operable member exposed above the plate and being electrically connected beneath the plate in a suitable motor energizing circuit.

The plate 12, outwardly of the turntable, may be provided with a pedestal 27 on which a pick-up device, comprising an arm 28, is pivoted for swinging movement about the vertical axis of the pedestal. The arm may also be mounted for movement about a horizontal axis at the top of the pedestal, so that a pick-up device at the swinging end of the arm may engage and may be raised from engagement with a record in playing position on the turntable. The pick-up device on the arm 28 may be connected with any suitable sound reproducing apparatus, so that, by applying the pick-up device to a record on the turntable and by operating the motor 22, the apparatus may reproduce the sounds recorded on the record.

Mechanism for the automatic delivery of records in playing position on the turntable may comprise magazine means for supporting a stack 29 of record discs, in position to be delivered successively into playing position on the turntable, the delivery mechanism including means operable for ejecting records successively from the stack onto the turntable. To this end, the magazine means may comprise a record stack supporting center pin 30 of preferably circular sectional configuration, said pin, at its lower end, being preferably removably receivable in the bushing 15, the bushing having an opening sized to snugly receive the end of the pin, and having a shoulder 31 adapted to mate with a tongue on the end of the pin for a purpose hereinafter more particularly described. The pin may thus be mounted in the bushing in position extending upwardly of the turntable.

The upper end of the pin comprises an offset

portion 32 defining an upwardly facing shoulder 33 on one side of the pin and a downwardly facing shoulder 34 on the other side thereof. Both the upper offset portion and the lower portion of the pin are sized to loosely fit the central opening provided in standard phonograph records of the disc type. Accordingly, one or more records forming a stack 29 may be applied to the offset portion 32 of the pin, said portion extending in the aligned center openings of the records, and the records being supported one upon the other, with the lowermost record of the stack resting upon the upwardly facing shoulder 33, said shoulder engaging the lowermost record of the stack on one side of the central opening thereof. It will be noted that all of the records in a stack, thus supported, with the exception of the lowermost record, are positively held in concentric alignment by the upper portions 32 of the center pin.

The shoulders 33 and 34 are spaced apart a distance slightly greater than the thickness of a record disk. Accordingly, the lowermost record in a stack may be moved on the center pin in a direction to align its central opening with the lower portions of the center pin, thereby disengaging said lowermost record from the shoulder 33. When so moved, the lowermost record will be free to fall, under the influence of gravity, downwardly along the lower portions of the center pin and become deposited on the turntable in position to be played.

In order thus to move the lowermost record, to release or eject it from the stack and deliver it in playing position on the turntable, edge pushing mechanism 35 may be provided. This pushing mechanism may comprise a support sleeve 36 extending through an opening 37 in the plate 12, in position outwardly of the edge of the turntable, the edge pushing mechanism being disposed on the side of the pin opposite from the upwardly facing shoulder 33 thereof. Since the edge pushing mechanism is permanently mounted on the plate 12, the shoulder 31 of the pin supporting bushing and the mating tongue of the center pin assure the mounting of the pin in the support bushing 15 only in position with the shoulder 33 facing away from the edge pushing mechanism.

The sleeve 36, at its lower end, beneath the support plate 12, is carried on a bracket 38 which, in turn, is pivotally mounted, as by means of the pivot pins 39, in a mounting bracket 40 fastened preferably to the underside of the plate 12. The sleeve 36 extends upwardly of the plate 12 and receives a stem 41 turnably therein, said stem carrying an edge pushing plate 42 at the upper end of the sleeve 36. This plate provides lips 43 and 43' at remote edge portions of the plate, and upstanding, struck-out fingers 44 disposed inwardly of said lips, the vertical length of the fingers being substantially equal to the thickness of a standard record disc. As shown, the lips 43 and 43' are formed in opposite edges of the plate 42, which is eccentrically mounted on the pin 41, the lips 43' being closer to the pin than the lips 43. By rotating the plate 42, either the lips 43 or the lips 43' may be disposed in position facing toward the center pin 30, the arrangement being such that the lips 43 and 43', when turned toward the pin 30, will extend in position to underlie and form edge support for the lowermost disc in a record stack carried by the center pin, the eccentric mounting of the plate 42 allowing the lips 43 to provide edge support for discs of the standard 10 inch size, while the lips 43' may afford support for standard 12 inch record discs.

The plate 42 carries a fitting 45 thereon between the lips 43 and 43', said fitting forming a mounting for a pivoted arm 46, the swinging end of which is provided with a weighted head 47. The fitting 45 includes spring means 48, preferably in the form of a leaf spring, adapted to operate upon the arm 46, in either direction, to provide a toggle action, whereby the arm may be swung on its pivot at will to bring the head 47 either into position above the lips 43, or above the lips 43', the spring urging the head downwardly toward the lips whereby the weighted head may be pressed downwardly upon the records of a supported stack in order to hold the edges thereof, either upon the edge supporting lips 43 or upon the lips 43'.

The stem 41 has an end projecting outwardly of the sleeve 36, below the bracket 38, and provided with a radially extending arm 49 carrying a lever actuating stud 50, which turns with the stem as the plate 42 is turned, to selectively present the lips 43 and 43' in operative stack supporting position. A spring 51 is preferably assembled on the stem between the arm 49 and the end of the sleeve 36, in order yieldingly to draw the stem 41, in the sleeve 36, in a direction to bear the plate 42 against the sleeve 36. One side of the sleeve 36, at the end thereof on which the plate 42 bears, is cut away, as at 52, to accommodate a latching pin 53, which may comprise either a radial pin in the stem 41 or a struck-out lug on the plate 42, in position to extend in and to ride upon the cut-away end of the sleeve 36. Said cut-out portion 52, at the opposite ends thereof, forms notches 54 adapted to latchingly receive the latch member 53 in order to latch the plate on the sleeve 36 in either of its turned positions, presenting the lips 43 or the lips 43' in stack supporting position.

The sleeve supporting bracket 38 is formed with a projecting arm 55 extending thence underneath the plate 12 toward the portions thereof beneath the central portions of the turntable, a tension spring 56 being connected between said arm 55 and the plate 12 to normally and yieldingly urge said arm and its connected bracket 38 in a direction on the pivots 39 to retract the plate 42 away from the center pin 30. The arm 55 is provided with preferably adjustable stop means, such as the screw 57, mounted on the arm 55 in position to engage the plate 12, and thus limit the tilting movement of the arm 55, the bracket 38 and the sleeve 36, and the resultant retracting movement of the plate 42, under the influence of the spring 56. The stop means 57 may thus be arranged normally to hold the plate 42 in such position as to present the lips 43 and 43' respectively in position to support the edges of standard 10 and 12 inch records, in stacks, with the lugs 44 lying against the edge of the lowermost record of a supported stack.

Whenever it is desired to feed the lowermost record of a supported stack into playing position on the turntable, the arm 55 may be moved against the urge of the spring 56 to shift the plate 42 toward the center pin 30, whereby the lugs 44 may shift the lowermost record of the supported stack radially on the pin 30 to release the same from the shoulder 33, the arm 55 being then released for return to normal position determined by the stop member 57, thus releasing both the edge and the center of said lowermost record for deposition by gravity into playing position on the turntable.

From the foregoing it will be apparent that the

7
present invention contemplates an exceedingly simple, inexpensive, yet novel and effective edge pushing mechanism for the successive ejection of record disks from a supported stack and the delivery thereof in playing position upon the turntable.

Simplified driving mechanism also is provided to operate the record feeding mechanism and to correlate the operation thereof with record playing movements of the pick-up arm 28. This driving mechanism may operate automatically for record disc feeding purposes by first lifting the arm 28 from a record being played, and swinging it to a retracted or stand-by position outwardly of the record. In performing its operating cycle the driving mechanism may then actuate the lever 55 for record feeding purposes in the manner previously described to deposit the lowermost record disc, in the stack 29, in playing position on the turntable. Finally, the driving mechanism may operate to advance the arm 28, inwardly with respect to the turntable, and deposit it upon the record disc in position to commence the playing thereof.

To these ends, the driving mechanism may comprise a rod or shaft 58 axially shiftable and turnably mounted in suitable bearings 59 and 59', respectively, mounted in brackets 60 and 60', supported on the underside of the plate 12, the shaft 58 being thus mounted beneath the plate 12 in position with one end of the shaft extending beneath the central portions of the turntable, and the other end projecting beneath the arm carrying pedestal 27. The shaft 58 carries a gear wheel 61 fixed thereto and preferably comprising a sheet metal stamping, in the interests of manufacturing economy. The gear wheel 61 may be strengthened and reinforced by means of a plate or disc 62 forming a hub at the central portions of the wheel. This hub preferably carries a latch pin 63 projecting therefrom in a direction parallel with respect to the axis of the shaft 58. The wheel and hub extend adjacent the bearing bracket 60, and the pin 63 projects toward said bracket. The bracket may be formed with a latch pin opening 64 in position to receive the pin 63 whereby to lock the shaft and the gear wheel against turning movement, in the bearings 59 and 59', when the shaft is in an axially retracted position. The edge of the gear wheel 61 extends in an opening 65 formed in the plate 12 whereby, when the shaft 58 is in axially projected position, in which the latch pin 63 is disengaged from the latch opening 64, the gear wheel 61 may drivingly engage the gear 29 on the turntable, the gear wheel 61 being retracted from driving engagement with the gear 29 and drivingly disconnected therefrom whenever the shaft 58 is in axially retracted position.

It will be apparent from the foregoing that the shaft 58, when in axially projected position, will be driven by the motor 22 through the turntable and the gear members 29 and 61; and, when the shaft 58 is in axially retracted position, it will be latched against rotation in a predetermined angular position in its bearings 59 and 59'. The shaft thus comprises a member periodically operable under the driving influence of the motor 22 to actuate the record feeding mechanism 35 and to swing and position the tone arm 28 in manner hereinafter more fully described. To this end the shaft 58 is cooperatively associated with the pick-up arm 28 by arm operating means extending within the pedestal 27 and operable to raise,

swing, and lower the pick-up arm in accordance with the movement of the shaft 58.

8
The pedestal 27 forms a vertical bearing for a tubular member 66, which is turnably mounted within the pedestal. One end of this tube extends at the upper end of the pedestal and carries a bracket 67 upon which the arm 28 is pivotally supported as by means of a horizontal pivot pin 68. The tube 66 has an end extending outwardly of the pedestal beneath the support plate 12, said end carrying an arm or blade 69 fixed thereon and extending radially outwardly of the tube and turnable therewith. This arm 69 accordingly moves about the axis of the pedestal 27 along with the pick-up arm 28.

Vertically movable within the bore of the tube 66, is a pin 70 having an end projecting upwardly of the bracket 67 in position to engage a bearing block 71 on the arm 28. At its lower end the pin 70 projects from the tube 66, beneath and adjacent the arm 69, and carries a disc 72 having a spline pin 73 projecting upwardly thereof, at the edge of the disc in position to extend through an opening in the arm 69, said arm preferably comprising a sheet metal stamping. The pin 70 accordingly may move upwardly and downwardly within the sleeve 66, carrying with it the disc 72, which is drivingly connected at all times with the sleeve 66, and hence with the pick-up arm 28 and the control arm 69, by means of the spline pin 73. The marginal portions of the plate 72, on the under side thereof, are roughened to form an annular frictional driving surface 72'; and the pin 70, beneath the disc 72 and centrally thereof, forms a cam following projection 74.

By moving the pin 70 up or down through the sleeve 66, the arm 28 may be raised or lowered on its pivot pin 68; and by turning the disc 72, the arm 28 may be swung horizontally about the axis of the pedestal 27. Suitable actuating means is provided for thus raising and lowering the arm 28, by the axial movement of the pin 70, and for swinging the arm 28, in response to the turning movement of the shaft 58 when the gears 29 and 61 are in driving engagement. Such actuating means may comprise an arm raising and lowering cam 75 and a pair of arm swinging segments 76 and 76' fixed on the end of the shaft 58 beneath the pedestal 27, said cam and segments being in position on the shaft such that, when the shaft is in axially projected driving position, the cam 75 will be in operative registration and engagement with the cam following projection 74 of the stem 70, and the elements 76 and 76' will be disposed beneath and in position to operatively engage the annular frictional driving surface 72' of the disc 72 respectively on opposite sides thereof.

The shaft 58 is normally urged toward projected driving position as by means of a compression spring 77, which conveniently may comprise a helical spring element encircling the shaft and bearing at opposite ends respectively on the bearing 59' and on a collar 78 forming a spring seat on the shaft. Means also is provided for holding the shaft in axially retracted or cocked position against the influence of the spring 77, said means conveniently comprising a latch collar 79 on the shaft and a latch member 80, preferably comprising a sheet metal stamping, pivotally mounted as on a pivot pin 81, in turn supported on the plate 12. The latch member has a latching tongue 82 and is normally urged, as by means of a spring 83, on the pin 81, into position to latchingly engage the latch collar 79 on

the shaft. The latch member 80 also preferably is formed with an operating arm 84 which extends toward the pedestal 21, said arm having a bearing portion 85 near its end in position to be engaged and pressed by the arm 69, in order to release the latch members 79 and 82 and thus release the shaft 58 for movement from cocked to driving position when the tone arm 28, during the playing of a record on the turntable, reaches and enters the usually eccentric terminal groove of the record disc. If desired the arm 69 may be fitted with an adjustable set screw 86 in position to engage the bearing portion 85 whereby accurately to determine the latch tripping position of the tone arm 28. The shaft 58 may thus be released from cocked to operating position for the performance of its operating cycle at the conclusion of the playing of a record disc, and the latching position of the member 80 under the influence of the spring 83 may be limited and determined by a stop pin 87, mounted on the plate 12 in position to engage the arm 84 when the latch member 80 is in latching position.

Upon release of the latch members 79 and 82, by action of the arm 69 at the conclusion of the playing of a record on the turntable, the shaft 58 will be turned, by the turning movement of the turntable, through one complete rotation of the shaft 58. During the course of said rotation a portion 88 of the cam 75 will operate to raise the tone arm 28 from the record. Thereafter the driving segment 76' will operate, through the disc 72 and sleeve 66, to swing the tone arm to a retracted position outwardly of the turntable determined by the engagement of the arm 69 with a stop 89 mounted on and extending beneath the plate 12. The driving segment 76' is so positioned on the shaft as to commence its driving engagement with the disc 72, as the result of turning movement of the shaft, as soon as the pin 78 has been lifted by the cam portion 88 to raise the arm 28 from engagement with the record on the turntable.

The gear 61 carries a pin 90 thereon in position to engage and operatively shift the actuating arm 55 of the disc feeding mechanism 35, said actuating arm having a cammed end 91 extending adjacent the gear wheel 61 in position to be drivingly engaged by the pin 90 during the rotation of the gear wheel, said arm 55 being operatively shifted by the pin 90, during the cycle of operation of the driving mechanism, immediately after the pick-up arm has been retracted to stand-by position outwardly of the record disc. Actuation of the arm 55, as previously described, will result in the delivery of a record from the stack 29, into playing position on the turntable.

Thereafter continued movement of the shaft 58 will bring the driving segment 76 into engagement with the disc 72 in order to swing the tone arm 28 into position to commence the playing of the record delivered on the turntable. So long as the segments 76 and 76' are driving the disc 72, the pin 78 and the arm 28 will be held in elevated position by said segments. During the interval after the segment 76' has retracted the arm and before the segment 76 operates to project the arm, it may be retained in elevated position by the riding of the cam follower element 74 upon a cam portion 92 of the cam member 75.

In order to stop the arm 28 in starting position at the edge of a record on the turntable, a stop latch 93 is provided. This latch preferably comprises a sheet metal plate pivotally mounted on and beneath the plate 12. Where standard 10" 75 28 has reached the commence playing position as

or 12" record discs are to be accommodated, the latch member 93 may be provided with a pair of stop shoulders 94 and 95 so that by positioning the stop member to present one or other of the shoulders 94 and 95 in the path of the tongue 69' of the arm 69, said arm and the pick-up arm 28 which is drivingly connected therewith may be stopped in appropriate starting positions for commencing the playing of 10" and 12" record discs.

10 Means is provided for positioning the shoulders 94 and 95 for cooperation with the tongue 69' in accordance with the adjusted position of the feeding mechanism 35 to accommodate either 10" or 12" record discs. To this end a preferably sheet metal lever 96 is provided on the under side of the plate 12 and mounted thereon for pivotal movement as on a support pin 97. This lever is connected with the latch member or plate 93 and has an end slotted as at 98 to receive the roller 50. Accordingly, the lever 96 will turn on its pivot and move the latch member or plate 93 to present one or other of the shoulders 94 or 95 in the path of the arm 69 in response to the turning of the plate 42 in adjusting the mechanism 35 for the accommodation of 10" and 12" records.

After the pick-up arm 28 has been stopped by one or other of the shoulders 94 or 95 in position to start the playing of a record, continued movement of the shaft 58, through the action of a cam portion 99 of the member 75, will lower the arm 28 upon the record. Means operable simultaneously with the lowering of the arm onto the record is also provided for releasing the tongue 69' from whichever of the shoulders 94 and 95 with which it is then in stopping engagement, in order to release the arm 28 for free playing movement in engagement with the helical sound grooves of the record disc.

To this end the stop lever or plate 93 is mounted on the adjusting lever 96 by means of a pivot pin 100, which pivotally interconnects mounting ears 101 and 102 formed respectively on the levers 96 and 93. Spring means, preferably a helical spring 103, encircling the pin 100, serves yieldingly to urge the member 93 on the pivot pin 100 in a downward direction from the plate 12 to present the shoulders 94 and 95 in the horizontal plane of the path of movement of the tongue 69'. The member 93, however, is provided with a downwardly extending plate portion 104 in position to be engaged by a cam member, such as the collar 78, on the shaft 58. This cam member preferably comprises a disc having a circular edge portion 105 adapted to engage the blade 104 in order normally to hold the member 93 against the influence of the spring 103 in position such that the shoulders 94 and 95 are displaced upwardly from the plane of movement of the tongue 69'. Accordingly, so long as the cam portion 105 engages the blade 104, the arm 69 and the pick-up arm 28 may swing freely without being stopped by either of the shoulders 94 and 95. A portion of the member 78, however, is cut away to form a flat cam surface 106, the member 78 being positioned on the shaft 58 so as to present such flat cam surface 106 to the blade 104, thereby allowing the member 93 to move, under the influence of the spring 103, into position presenting the shoulders 94 and 95 in stopping position in the plane of movement of the tongue 69' at the instant when the shaft 58, by operation of the member 76, starts to project the arm 28 from retracted stand-by position toward its commence playing position.

As the shaft 58 continues to turn after the arm 75 28 has reached the commence playing position as

determined by the shoulder 94 or the shoulder 95, the member 78 will also turn and retract the member 93 from stopping position by presenting the circular cam portion 105 in lifting engagement with the blade 104, thus releasing the arm 28 for free record playing movement across the turntable.

After completion of the record changing and arm swinging operations, the shaft 58 will continue to be driven until the gear wheel 61 reaches a resetting position in which the pin 63 comes into alignment with the latch opening 64. As the gear wheel reaches such position, a cam member on the gear wheel, such as the pin 90, comes into engagement with a resetting member, the same preferably comprising a lever 107 pivotally mounted on a suitable support bracket on the plate 12. This lever is normally urged as by means of a spring 108 into position in the path of the pin 90, so that as the gear wheel 61 approaches its resetting position, it will engage and depress the resetting lever 107, against the influence of the spring, so that, as the wheel reaches the resetting position, the urge of the spring 108 will be applied to the end of the pin 90 in a direction parallel to the axis of the shaft 58, the spring 108 being strong enough to urge the gear and the shaft 58 toward axially retracted position, against the spring 71.

The end of the pin 63, accordingly, will ride upon the face of the bracket 60, maintaining the gears 20 and 61 in engagement, until the pin 63 registers with the opening 64, at which instant the gear 61 and shaft 58 will be pushed to retracted position by lever 107, locking the pin 63 in the opening 64, disconnecting the gear 61 from the gear 20, and allowing the latch member 82 to assume its latching position against the face of the latching collar 79 to hold the shaft 58 latched in retracted locked position, ready for a repeat cycle of its record feeding and pick-up arm swinging operation. The axial relatching movement of the shaft also disengages the pin 90 from the lever 107, after the collar 79 has been moved slightly farther than required to allow the latch 82 to engage it. The lever 107 then slips off the end of pin 90 allowing shaft 58 to move, under the influence of spring 71, to bring the face of member 79 into holding engagement with the latch 82.

It will be seen from the foregoing that the mechanism provides for the complete automatic operation of the record feeding and arm swinging apparatus in response to the tripping of the latch member 80 at the conclusion of the playing of a record. Means is provided, however, for initiating the record changing cycle of operation at any time during the playing of a record, whereby to accomplish a so-called "record reject" function. To this end the latch member 80 may be formed with a flange or ear 109 disposed in position to be engaged by a lug 110 on a bar 111, slidably secured on the support plate 12 as by means of a headed pin 112, on the plate 12, and an elongated slot 113 formed in the bar. This bar 111 extends beneath the plate 12 to a convenient position outwardly of the turntable. A manually operable knob 114 mounted for sliding movement on the upper surface of the plate 12, in readily accessible position, may be connected with the bar 111 as by means of a fastening screw 115 extending through an elongated slot 116 formed in the plate 12. The bar 111 in its edge may be cut out as at 117 to provide a pair of adjacent latch-receiving notches 118 and 119.

A latch spring 120 may be mounted on the under side of the plate 12, said spring having a latching portion 121 in position extending in the cut out portion 117 of the bar 111. The bar may be shifted by means of the knob to engage the latch spring in the notch 118. When in such position a latching extension 122 on the bar 111 will engage and permanently latch with the collar 79 on the shaft 58, thus preventing automatic operation of the record changing mechanism. When the shaft 58 is so latched by the bar 111, the record player will be conditioned for so-called "manual" operation. By moving the bar 111 to engage the latch spring with the notch 119, the latching tongue 122 will be released from the collar 79 in order to condition the apparatus for automatic record changing operation, this being the normal or neutral position of the bar 111. By further projecting the bar 111, the latching end 121 of the spring may be caused to ride upon an inclined shoulder 123 of the cut out bar portion in order to engage the releasing lip 119 of the bar with the actuating lug 109 of the latch member 82, whereby to move said member 82 in a direction to release the latch member 82 from the latch collar 79, and thus initiate the record changing cycle of operation manually for "record reject" purposes.

It will be seen from the foregoing that the mechanism affords exceedingly simple and inexpensive record playing apparatus, in that substantially all of the parts, including the gear 20 and the gear wheel 61, may comprise sheet metal stampings, while the other parts may comprise simple elements cut from standard stock on automatic machines. Exceedingly simple control means is provided for conditioning the apparatus either for manual or automatic operation. The mechanism also provides means manually operable at any time, during the playing of a record, for discontinuing and rejecting such record and delivering a succeeding record disc from the magazine.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. Phonographic apparatus comprising a record turntable adapted to be driven, a tone arm, driving means operatively associated with the turntable and driven thereby, driven means connected on a turntable and axially shiftable shaft in coactive relation with said driving means, means operatively associated with said shaft and said tone arm to raise and lower the same, means operatively associated with said shaft and said tone arm to move the tone arm laterally away from the turntable and to move the tone arm toward the turntable after it has been moved away from the turntable, and means operatively associated with said shaft for retracting said shaft to disengage said driven means for coactive relation with said driving means.

2. Phonographic apparatus comprising a record turntable adapted to be driven, a tone arm, driving means operatively associated with the turntable and driven thereby, driven means connected on a turntable and axially shiftable shaft

in coactive relation with said driving means, means operatively associated with said shaft and said tone arm to raise and lower the same, means operatively associated with said shaft and said tone arm to move the tone arm laterally away from the turntable and to move the tone arm toward the turntable after it has been moved away from the turntable, means operatively associated with said shaft for retracting said shaft to disengage said driven means from coactive relation with said driving means, and means operatively associated with said shaft for holding said shaft in said retracted position during the record playing operation.

3. Phonographic apparatus comprising a record turntable adapted to be driven, a tone arm, driving means operatively associated with the turntable and driven thereby, driven means connected on a rotatable and axially shiftable shaft in coactive relation with said driving means, means operatively associated with said shaft and said tone arm to raise and lower the same, means operatively associated with said shaft and said tone arm to move the tone arm laterally away from the turntable and to move the tone arm toward the turntable after it has been moved away from the turntable, means operatively associated with said shaft for retracting said shaft to disengage said driven means from coactive relation with said driving means, and means operatively associated with said shaft for locking said shaft against rotation in said retracted position.

4. Phonographic apparatus comprising a record turntable adapted to be driven, a tone arm, driving means operatively associated with the turntable and driven thereby, driven means comprising a rotatable and axially shiftable shaft in coactive relation with said driving means, means operatively associated with said shaft and said tone arm to raise and lower the same, means operatively associated with said shaft and said tone arm to move the tone arm laterally away from the turntable and to move the tone arm toward the turntable after it has been moved away from the turntable, means operatively associated with said shaft for retracting said shaft to disengage said driven means from coactive relation with said driving means, and means operatively associated with said driven means to project said shaft axially into driving relationship with said driving means from said retracted position.

5. Phonographic apparatus comprising a combination of a record turntable adapted to be driven, a tone arm, driving means operatively associated with the turntable and driven thereby, axially shiftable driven means connected on a rotatable and axially shiftable shaft in coactive relation with said driving means, means operatively associated with said shaft and said tone arm comprising a cam wheel rotatable with said shaft, means operatively connected with said cam wheel and engaging the tone arm to raise and lower the same, segmental frictional driving members rotatable with said shaft and adapted upon rotation of said shaft in one direction to successively engage a turntable element on opposite sides of its turning axis to thereby successively turn said element in opposite directions, a connection between said turntable element and said tone arm to cause said tone arm to turn with said element in one direction away from and in another direction toward playing position, means operatively associated with said

shaft for retracting said shaft to a position in which it is out of driving engagement with said driving means during the playing of a record, and means operatively associated with said shaft for holding said shaft in said retracted position during the record playing operation.

6. Phonographic apparatus comprising a combination of a record turntable adapted to be driven, a tone arm, record changing means, driving means operatively associated with the turntable and driven thereby, driven means comprising a rotatable and axially shiftable shaft in coactive relation with said driving means during a record changing operation, means operatively associated with said driven means and said record changing means to effect a record changing operation, means operatively associated with said shaft and said tone arm to raise and lower the same prior to and after the record changing operation, means operatively associated with said shaft and said tone arm to move the tone arm laterally away from the turntable just prior to said record changing operation and to move said tone arm laterally toward said turntable just after said record changing operation, and means operatively associated with said driven means for retracting said shaft axially until said driven means is out of said coactive relation with said driving means during the playing of a record.

7. Phonographic apparatus comprising a combination of a record turntable adapted to be driven, a tone arm, record changing means, driving means operatively associated with the turntable and driven thereby, driven means comprising a rotatable and axially shiftable shaft in coactive relation with said driving means during a record changing operation, means operatively associated with said driven means and said record changing means to effect a record changing operation, means operatively associated with said shaft and said tone arm to raise and lower the same prior to and after the record changing operation, means operatively associated with said shaft and said tone arm to move the tone arm laterally away from the turntable just prior to said record changing operation and to move said tone arm laterally toward said turntable just after said record changing operation, means operatively associated with said driven means for retracting said shaft axially until said driven means is out of said coactive relation with said driving means during the playing of a record, and means operatively associated with said shaft for holding said shaft in said retracted position during the record playing operation.

8. Phonographic apparatus comprising a combination of a record turntable adapted to be driven, a tone arm, record changing means, means to raise and lower the tone arm and to move the tone arm laterally away from and toward the turntable, driving means operatively associated with the turntable and driven thereby, driven means comprising a rotatable and axially shiftable shaft in coactive relation with said driving means during a record changing operation, means operatively associated with said driven means and said record changing means to effect a record changing operation, means operatively associated with said shaft and said tone arm to raise and lower the same prior to and after the record changing operation, means operatively associated with said shaft and said tone arm to move the tone arm laterally away from the turntable just prior to said record changing operation and to move said tone arm laterally toward said turntable just after said record changing operation.

table just after said record changing operation, means operatively associated with said driven means for retracting said shaft axially until said driven means is out of said coactive relation with said driving means during the playing of a record, means operatively associated with said shaft for holding said shaft in said retracted position during the record playing operation, and means operatively associated with said shaft for locking said shaft against rotation in said retracted position.

9. Phonographic apparatus comprising a combination of a record turntable adapted to be driven, a tone arm, record changing means, driving means operatively associated with the turntable and driven thereby, said driving means comprising a gear with angular teeth, driven means comprising a gear with angular teeth connected on a rotatable and axially shiftable shaft in coactive relation with the gear of said driving means during a record changing operation, means operatively associated with said driven gear and with said record changing means to effect the changing of a record, means operatively associated with said shaft and said tone arm to raise and lower the tone arm prior to and after the record changing operation, means operatively associated with said shaft and said tone arm to move the tone arm laterally away from the turntable just prior to said record changing operation and to move said tone arm laterally toward said turntable just after said record changing operation, and means operatively associated with said shaft for retracting said shaft until said driven gear is out of said coactive relation with said driving gear.

10. Phonographic apparatus comprising a combination of a record turntable adapted to be driven, a tone arm, record changing means, driving means operatively associated with the turntable and driven thereby, said driving means comprising a gear with angular teeth, driven means comprising a gear with angular teeth connected on a rotatable and axially shiftable shaft in coactive relation with the gear of said driving means during a record changing operation, means operatively associated with said driven gear and with said record changing means to effect the changing of a record, means operatively associated with said shaft and said tone arm to raise and lower the tone arm prior to and after the record changing operation, means operatively associated with said shaft and said tone arm to move the tone arm laterally away from the turntable just prior to said record changing operation and to move said tone arm laterally toward said turntable just after said record changing operation, means operatively associated with said driven means for retracting said shaft axially until said driven gear is out of said coactive relation with said driving gear, means operatively associated with said shaft for holding said shaft in said retracted position during the playing of a record, and means operatively associated with said driven means for protecting said driven gear from said retracted position into driving relationship within said driving gear.

11. Phonographic apparatus comprising a combination of a record turntable adapted to be driven, a tone arm, a record changing means, driving means operatively associated with the turntable and driven thereby, axially shiftable driven means connected on a rotatable and axially shiftable shaft in coactive relation with said driving means during a record changing operation, means operatively associated with said driven means and with said record changing

means to effect the changing of a record, means operatively associated with said shaft and said tone arm comprising a cam on said shaft adapted to raise and lower a member in contact with said

5 tone arm to raise and lower the tone arm prior to and after the record changing operation respectively, means operatively associated with said shaft comprising segmental frictional driving members rotatable with said shaft and adapted 10 upon rotation of the shaft in one direction to successively engage a turnable element on opposite sides of its turning axis to thereby successively turn said element in opposite directions, means connecting said turnable element to the tone arm 15 to cause the tone arm to rotate with said turnable element laterally away from the turntable just prior to said record changing operation and laterally toward the turntable just after the record changing operation, means operatively associated 20 with said shaft for retracting it until said driven means is out of said coactive relation with said driving means, and means operatively associated with said shaft for holding said shaft in said retracted position during the record playing operation.

12. Phonographic apparatus comprising a combination of a record turntable, means operatively associated with the turntable for turning the same, a tone arm, means above the turntable to 30 support a stack of records, record discharge means to discharge records successively from the bottom of the stack one at a time on to the turntable, driving means operatively associated with the turntable and driven thereby, axially shiftable 35 driven means comprising a gear wheel connected on a turnable and axially shiftable shaft in coactive relation with said driving means during a record changing operation, means operatively associated with said gear wheel and said record 40 discharge means to effect the record discharge operation, means operatively associated with said shaft and said tone arm to raise and lower the same prior to and after the record discharge operation, means operatively associated with said 45 shaft and said tone arm to move the tone arm laterally away from the turntable just prior to said record discharge operation and to move said tone arm laterally toward said turntable just after said record discharge operation, means operatively associated with said driven means for retracting 50 said shaft until said gear wheel is out of said coactive relation during the playing of a record and means operatively associated with said shaft for holding said shaft in said retracted position during the record playing operation.

13. Phonographic apparatus comprising a combination of a record turntable, means operatively associated with the turntable for turning the same, a tone arm, means above the turntable to 60 support a stack of records, record discharge means to discharge records successively from the bottom of the stack one at a time on to the turntable, driving means operatively associated with the turntable and driven thereby, axially shiftable 65 driven means comprising a gear wheel connected on a turnable and axially shiftable shaft in coactive relation with said driving means during a record changing operation, means operatively associated with said gear wheel and said record discharge means to effect the record discharge operation, means operatively associated with said shaft and said tone arm to raise and lower the same prior to and after the record discharge operation, means operatively associated with said 70 shaft and said tone arm to move the tone arm

laterally away from the turntable just prior to said record discharge operation and to move said tone arm laterally toward said turntable just after said record discharge operation, means operatively associated with said driven means for retracting said shaft until said gear wheel is out of said coactive relation during the playing of a record, means operatively associated with said shaft for holding said shaft in said retracted position during the record playing operation, and means operatively associated with said driven means for locking the same against rotation in said retracted position.

14. Phonographic apparatus comprising a combination of a record turntable, means operatively associated with the turntable for turning the same, a tone arm, means above the turntable to support a stack of records, record discharge means to discharge records successively from the bottom of the stack one at a time on to the turntable, driving means operatively associated with the turntable and driven thereby, axially shiftable driven means comprising a bevel gear wheel connected on a rotatable and axially shiftable shaft in coactive relation with said driving means during a record changing operation, means operatively associated with said gear wheel and said record discharge means to effect the record discharge operation, means operatively associated with said shaft and said tone arm to raise and lower the same prior to and after the record discharge op-

eration, means operatively associated with said shaft and said tone arm to move the tone arm laterally away from the turntable just prior to said record discharge operation and to move said tone arm laterally toward said turntable just after said record discharge operation, means operatively associated with said driven means for retracting said shaft until said gear wheel is out of said coactive relation during the playing of a record, means operatively associated with said shaft for holding said shaft in said retracted position during the record playing operation, means operatively associated with said shaft for locking said shaft against rotation in said retracted position, and means operatively associated with said driven means for projecting said shaft axially from said retracted position to a position in which said driving means and said driven means are in said coactive relation.
